JAMES HARRIS, OF JANEVILLE, WISCONSIN.

Letters Patent No. 87,101, dated February 23, 1869.

IMPROVEMENT IN CULTIVATORS.

The Schedule referred to in these Letters Patent and making part of the same.

To all whom it may concern:

Be it known that I, JAMES HARRIS, of the city of Janesville, in the county of Rock, and State of Wisconsin, have invented certain new and useful Improvements in Cultivators; and I do hereby declare that the following is a full, clear, and exact description thereof, reference being had to the accompanying drawings, making a part of this specification, in which—

Figure 1 is a side view or elevation of the "drag-bar" and tooth or shovel of a cultivator, as I construct them, and as they appear when in use;

Figure 2 is also a side view or elevation of the same as they appear when the cultivator is "backing;"

Figure 3 is a longitudinal vertical section of the same as they appear when the tooth has been released by coming in contact with an obstruction; and

Figure 4 is a top view of a portion of two drag-bars, showing their position in connection with the "draught-rod."

The nature of my invention relates to the teeth and drag-bars of cultivators, and consists—

First, in connecting the shank of the tooth to an independent circle-iron, when constructed and used in connection with the "drag-bar," substantially as and for the purpose hereinafter described.

Second, in joining the drag-bar to the "draught-rod," by means of an elongated metallic box-bearing, substantially as and for the purpose hereinafter described.

To enable others skilled in the art to make and use my invention, I will proceed to describe its construction and operation.

In the drawings—

A represents a drag-bar, of wood, or other suitable material;

B, the tooth;

C, the circle-iron; and

D, the elongated metallic box joining the drag-bar A to the draught-rod K, fig. 4.

The tooth at the end of the shank, and the circle-iron at its upper end, have a common bearing on the pivot-pin *a* that passes through the drag-bar.

The lower end of the circle-iron is joined to the shank of the tooth by a safety-coupling, *b*.

This safety-coupling consists of a simple bolt passing through the shank, and also through a slot, *c*, in the circle-iron.

On the end of the bolt is a washer, larger than the width of the slot, and a nut to clamp them together.

The nut may be in the circle-iron and the slot in a flange or short ear on the shank, if desired, or a bolt-staple in the shank, clasping around the circle-iron, and dispensing with the slot, may be used.

To set the teeth, or to give them the desired "pitch," or inclination, I pierce the circle-iron with a series of

holes, *d*, through either of which the setting-device *E* may be secured.

This setting-device may consist of the bolt and square-faced lugs, as shown, or of the simple pin *l*, shown in fig. 3. In the latter case, the upper face of the drag-bar (if of wood) should be covered with a metallic plate, to prevent the pin from indenting the wood.

The elongated box-bearing D should be of cast-iron, of the form shown, in which case the forward end of the drag-bar should be slotted to receive it, and the same secured therein by a bolt, *f*, passing through the flange *h*.

The box is bored or cast with orifice *e*, so as to nicely fit on the draught-rod K, fig. 4, and extends beyond the drag-bar, on either side, one-half of the width of the space between the bars.

The position of the drag-bars on the draught-rod, and the office of the elongated box-bearing, are shown in fig. 4.

As heretofore joined to the draught-rod, it has been impossible to keep the drag-bars (and teeth) in line, as, owing to their short bearing on the draught-rod, they were constantly swinging and swaying sidewise.

As heretofore constructed, it has been the custom, in order to keep the bars the proper distance apart, to fill the space between them on the draught-rod with washers.

To avoid the use of washers, and to keep them securely in line, by giving them a broad, firm bearing on the rod, I employ the elongated metallic box described.

It is not essential to my invention that the box D should be inserted in a slot in the drag-bar, as the same results may be accomplished by bolting it underneath or on the top of the bar, or by constructing it in sections and bolting them upon the sides thereof.

It will be seen that the adjustable setting-device *E* secures without change, when once set, the pitch or inclination of the teeth, and allows them to swing forward, as shown in fig. 2, when the cultivator is backed.

It will also be seen that the safety-coupling *b* holds the teeth with an adjustable force, and when once the tooth is drawn back by an obstruction, the short distance necessary to withdraw the bolt from the slot *c*, the tooth is not still held by the coupling, but is entirely free; also, that the freeing or loosening of the tooth does not affect the previous setting of its pitch or inclination, which remains unchanged, however often the tooth may be loosened.

What I claim, is—

1. The detached or independent circle-iron C.
2. The arrangement of the detached circle-iron C with the tooth B, whereby both have a common bearing on the pivot-pin *a*, substantially as described.

3. The combination of the tooth B, circle-iron C, and coupling-device *b*, substantially as described.

4. The arrangement of the tooth B, independent circle-iron C, setting-device E, and drag-bar A, substantially as and for the purpose described.

5. The combination and arrangement of the tooth B and independent circle-iron C, when joined by the coupling-device *b*, and having a common bearing, *a*, with the drag-bar A and setting-device E, or pin *l*, substantially as described.

6. Joining the drag-bars to the draught-rod by means of the elongated metallic box D, whereby a broad, firm bearing is secured, and washers between the bars dispensed with, substantially as described.

JAMES HARRIS.
